UNITED STATES PATENT OFFICE.

ANDREW J. RIDGEWAY, OF MILL CREEK, WEST VIRGINIA.

IMPROVEMENT IN BURGLAR-ALARMS.

Specification forming part of Letters Patent No. **222,533**, dated December 9, 1879; application filed October 10, 1879.

To all whom it may concern:

Be it known that I, ANDREW J. RIDGEWAY, of Mill Creek, in the county of Berkeley and State of West Virginia, have invented certain new and useful Improvements in Burglar-Alarms, of which the following is a specification.

My object is to produce a device which may be used as a burglar-alarm, and also as a species of trap for animals.

My invention consists in the combination of parts operating together as I will now set forth in detail; but to avoid repetition, and in order that it may be better understood, I reserve the succinct definitive statement of my invention to be made in my claim.

My burglar-alarm belongs to that class of alarms which cause the lighting of a lamp, the ringing of a bell, or the firing of a shot; and I provide for the accomplishment of either one of these objects alone, or of all three together, as may be desired.

In the accompanying drawings, which illustrate my invention, Figure 1 is a plan view, showing the alarm set. Fig. 2 is a plan view, showing the alarm unset; and Fig. 3 is a side elevation, showing the alarm unset.

A indicates a bed-plate, to which my apparatus is applied. In this bed-plate is formed a groove, a, in which slides a rod, B, connected at the rear end to a pivoted trigger, C, which is pressed against by a spring, D, to keep it normally in position for engaging with a catch, E, upon the rear end of the plunger F. This plunger is secured by guides G G upon the surface of the bed-plate, and is provided on its front end with percussion-hammers. A pistol-barrel, H, having one or more bores, so as to contain either one or several charges, is placed in front of the plunger in such a position as to be struck by the percussion-hammers.

I have shown this pistol-barrel as adapted for breech-loading cartridges; but it may be provided with nipples for the reception of caps, to be adapted to muzzle-loading, if preferred.

The plunger contains within its interior a strong coiled spring sufficient to throw it forward with the necessary force. The bell I is fixed, by means of a coil-spring, i, to the bed-plate, and it is so notched that it can be engaged with a catch, K, upon the outside of the plunger when the plunger is retracted.

The bell may be placed upon the plunger, if

preferred, and the catch may be properly secured to the bed-plate to hold it when the plunger is drawn back. A projection, I, is placed upon the plunger and carries a grater-like surface—such, for instance, as a piece of sand-paper—for the purpose of lighting a match, which may be held in proper position in the pivoted arm M immediately over a lamp, N, resting on the bed-plate and held by any suitable appliance. The object of pivoting the match-arm is, that it may be turned down out of the way for packing, or when it is not in use.

Supposing the pistol-barrels, or one of them, to be loaded, and the match to be in place, and the lamp to be trimmed ready for lighting, to set the alarm it is only necessary to draw back the plunger by means of a suitable ring or handle, when the catch E will engage with the trigger and hold the plunger in the retracted position. The bell can then be engaged with its catch K.

If the alarm is set for an animal, the rod B should be baited in front of the pistol, and the alarm will be fired by any interference with the bait.

When the apparatus is set for animals, it will, of course, not be necessary to either light the lamp or ring the bell.

If the device be set for a burglar, a cord or wire should be connected to the trigger and to a door or window or window-blind in such manner that any disturbance of either will pull the trigger and set off the alarm.

Having described the construction and operation of my improved alarm, what I claim as new, and desire to secure by Letters Patent, is—

The combination of the spring-plunger provided with the catch K, the trigger, trigger-spring, and catch E with rod B, pistol-barrel H, pivoted match-support M, match-lighting projection I, and alarm-bell mounted upon a spring and provided with a notch, all constructed, arranged, and operating together as set forth, whereby a shot may be fired, a light made, and a bell rung simultaneously, as specified.

In testimony whereof I have hereunto subscribed my name.

ANDREW J. RIDGEWAY.
